UNITED STATES PATENT OFFICE.

JOHN B. GREENHALGH, OF BLACKSTONE, MASSACHUSETTS.

LAMP-BURNER.

SPECIFICATION forming part of Letters Patent No. 275,901, dated April 17, 1883.

Application filed February 5, 1883. (No model.)

To all whom it may concern:

Be it known that I, JOHN B. GREENHALGH, of Blackstone, Worcester county, Massachusetts, have invented a new and useful Improvement in Lamp-Burners, of which the following is a full, clear, and exact description.

My invention relates to that class of lamp-burners that are provided with means for extinguishing the flame of the lamp in case the lamp should be accidentally upset; and it consists of the construction, arrangement, and combination of parts, all as hereinafter described and claimed.

Reference is to be had to the accompanying drawings, forming part of this specification, in which similar letters of reference indicate corresponding parts in all the figures.

Figure 1 is a side elevation of a lamp and lamp-burner provided with my invention. Fig. 2 is a perspective view of the slotted plate used for closing the pivoted extinguishing-plates over the lamp-wick, and Fig. 3 is a perspective view of one of the extinguishing-plates removed from the burner.

The main parts of the burner A may be of any approved construction.

b b are the extinguishing-plates, that are hinged under the dome C, near the wick-tube a, and are formed or provided with the arms e e, which project outwardly, as shown clearly in the drawings, and pass through the diagonal slots c c, made in the plate d. This plate d is formed with the stem d', which passes down through the flange g of the burner, where it is turned to form a hook for the attachment thereto of the upper end of the rod f. This rod f reaches down the bowl-handle and base of the lamp and rests upon the table or other support of the lamp when the lamp stands upright, as shown in Fig. 1, and is of such length relative to the height of the lamp that when the lamp is in upright position it lifts the plate d, causing the slots c c to open and hold open the extinguishing-plates b b, as shown in

Fig. 1. The rod is guided by the loops i i', formed in the rings h h', and is formed with the stud j, and upon the rod between the stud j and the eye i is placed the coiled spring k, which serves, should the lamp be upset, to force downward the rod f, which will draw downward the plate d and cause the diagonal slots c therein, acting upon the pins e e, to close the extinguishing-plates b b over the wick, and thus instantly extinguish the flame. The stud j serves also as a means by which the rod f may be held from downward movement by one finger of the hand when the lamp is lifted off from the table or other support.

Constructed in this manner it will be seen that all danger of conflagration from the upsetting of lamps is obviated, since the extinguishing-plates will close over the wick and put out the flame instantly upon the lamp tilting from its support. Besides, the device is cheap and may be applied to all forms of lamps.

Instead of having the rod f pass down the outside of the bowl and handle of the lamp, the handle might be made hollow and the bowl provided with a tube, through which the rod might be passed down to the face of the lamp, and thus conceal the rod.

I am aware that it is not broadly new in lamp-burners to use hinged hoods adapted, in case of a fall, to be operated by a weight or spring; but

What I do claim as new and of my invention is—

In a lamp-burner, the plate d, having diagonal slots c c, converging upwardly toward each other, and having a stem passing through the burner-flange g, in combination with the plates b b, hinged near the wick-tube under dome C, and provided with arms e e, passing through said slots, as shown and described.

JOHN B. GREENHALGH.
